UNITED STATES PATENT OFFICE.

MURRAY C. DAMON, OF LEOMINSTER, MASSACHUSETTS, ASSIGNOR TO THE HAIRLIGHT COMPANY, A CORPORATION OF MASSACHUSETTS.

HAIR ROLL OR PUFF.

Application filed December 19, 1921. Serial No. 523,267.

To all whom it may concern:

Be it known that I, MURRAY C. DAMON, a citizen of the United States, residing at Leominster, in the county of Worcester 5 and State of Massachusetts, have invented a new and useful Hair Roll or Puff, of which the following is a specification.

This invention relates to a hair roll or puff of that type in which a curved light 10 and flexible body, usually of a circular cross section, is applied to and held in the hair by means of a comb or combs attached thereto.

The principal object of the present invention is to provide a way of attaching the combs to the roll or puff that will permit 15 of the extension of the latter longitudinally and its subsequent contraction without releasing it from its connection with the comb 20 itself; and to provide this arrangement in such a simple and inexpensive form that this additional function can be secured without really adding to the expense of the device.

Reference is to be had to the accompanying drawings, in which—

Fig. 1 is a plan view of a hair puff or roll with a preferred embodiment of this invention applied thereto;

Fig. 2 is an inside elevation of the same, and

Fig. 3 is a plan view of a modified construction.

In the form shown in the first two figures, 35 I have illustrated the invention as applied to a puff or roll 10 formed in the shape of a tubular fabric of spring wire. It is to be understood however that I do not wish to limit the invention to this particular form 40 of roll as it can be applied to rolls formed of other fabrics and materials. It will not be necessary to describe this in detail as the form illustrated is well known.

It has been customary heretofore to attach a comb, as 11, rigidly to such puffs or rolls at two or more points. This eliminated one advantage of the tubular puff, namely its extensibility, and although these devices have been used for a number of 50 years, some with combs and some without, the fact that those without combs could be drawn out and increased or decreased in length while those with combs could not be, has not, so far as I am aware, resulted in

any attempt being made to secure the advantage of extensibility for the device having the comb thereon. I find that such extensibility is very desirable in certain cases.

I have provided for securing these results by attaching the comb to the puff or roll 60 centrally and positively by a wire 12, and by providing a movable or sliding connection between the comb and the puff or roll on each side of this central rigid connection. The form of the sliding connection 65 shown in Figs. 1 and 2 consists of a longitudinal slot 13 on each side of the center of the back of the comb, together with a connecting device. This connecting device is shown in the form of a headed stud 14, 70 the shank of which passes through the slot 13, and also between the meshes of the roll or puff 10. Inside the same there is a retaining plate or bar 15 to which the shank of the head is connected, preferably detachably, but in such a way that it is not possible for it to be detached instantly in ordinary use. This bar, being inside the puff, 75 can move and the shank, passing through the meshes of the puff, will move with it, 80 if the puff is extended. This forms a guide which will insure that the inner wall of the puff is in contact with the concave comb throughout its length no matter whether the puff is contracted or expanded. It also 85 causes the puff and comb to be kept in longitudinal alignment.

In the use of the device the wearer grasps the puff in the two hands and moves the comb down in the hair at the rear of the head, and at the same time is able to draw the puff out longitudinally at both ends so as to fix it nicely in position in the hair. This leaves the puff free to move if the hair in which it is located is in such position as 95 to allow it to. In other words, it gives flexibility to it, and allows it to assume any natural position which may be desired. It does not disturb the position of the comb which remains central at all times, and it enables 100 the user to employ a single puff to secure varying effects. It is especially advantageous for use with small hats.

Other guiding and connecting arrangements can be used within the scope of the 105 invention as expressed in the claims. I have shown one of these in the form illustrated in Fig. 3. Here the same principle is main-

tained, but in this case nothing passes through the puff on the inside, the comb 11 being connected with the puff by means of a connection that surrounds the 5 latter. This consists, in the form shown, of a pivot piece 20 secured to the back of the comb near its end and a ring 21 of celluloid, rubber, cord, or the like pivoted to this pivot piece and surrounding the puff or roll. Any 10 other fastening device, as for example, a wire or elastic, can be passed around it for the same purpose. It has the same effect as in the other case, the holding of the puff or roll against the back of the comb in all 15 positions, alignment, and perfect freedom of adjustment of the former.

Although I have illustrated and described only two specific embodiments of the invention I am aware of the fact that many other 20 modifications may be made therein by any person skilled in the art without departing from the scope of the invention as expressed in the claims. Therefore I do not wish to be limited to all the details of construction 25 herein shown and described, but what I do claim is:—

1. As an article of manufacture, a hair roll or puff provided with a comb secured centrally thereof at one point on the concave 30 side, and means on opposite sides of said point for adjustably connecting the comb with the puff and keeping the puff in con-

tact with the back of the comb in all adjusted positions.

2. The combination with an expansible 35 hair roll or puff in curved form, of a curved comb for attachment to the hair fixedly secured to the concave side thereof at a point central with respect thereto, and means slidably connecting the comb and puff on opposite sides of said central point for keeping them in longitudinal alignment in all adjusted positions.

3. The combination with a hollow expansible hair roll or puff, of a comb for attachment to the hair fixedly connected to the side thereof, and means on the comb a distance from the connection and extending inside the roll for adjustably connecting it with the puff or roll. 45

4. The combination with a tubular expansible hair roll or puff, of a comb for attachment to the hair fixedly secured to the side thereof at a central point, guides connected with the back of the comb, headed studs passing into said guides, and bars at the rear ends of said studs located inside the tubular puff or roll, said heads having shanks extending through the meshes of the puff or roll and connected with the bar. 55

In testimony whereof I have hereunto affixed my signature.

MURRAY C. DAMON.
